CONTINUOUS STRIP SLOT INSULATION

Richard O. Goldberg, Chicago, Ill., assignor to
 Pioneer Gen-E-Motor Corporation, Chicago,
 Ill., a corporation of Delaware

Application February 7, 1947, Serial No. 727,096

14 Claims. (Cl. 171—206)

1

My invention relates to improvement in continuous strip slot insulators and has for one object to provide a new and improved type of insulation which may be used to insulate the windings of an electrical rotor.

Another object of the invention is to provide in a single strip, which may be easily and conveniently assembled with the rotor, the insulating means lining the slots between the rotor poles.

Other objects of the invention will appear from time to time in the specification.

My invention is illustrated more or less diagrammatically in the accompanying drawings wherein:

Figure 1 is a side elevation of the rotor;

Figure 2 is a section view along the line 2—2 of Figure 1;

Figure 3 is a section view on a large scale along the line 3—3 of Figure 1;

Figure 4 is a plan view of the insulating strip in its extended position;

Figure 5 is a side elevation of the strip as assembled ready for installation; and

Figure 6 is a section view along the line 6—6 of Figure 3.

The invention is illustrated in the drawings as applied to a suitable type of electric rotor, but it will be understood that the application is merely illustrative, and the insulating strip might be used with many different types of rotors.

1 is a rotor shaft the details of which form no part of the invention. 2 is an insulating sleeve on the rotor shaft. 3 is the rotor mounted on the shaft 1 and having between it and the shaft the insulating sleeve 2. The rotor comprises an annular portion 4. Projecting therefrom are a plurality of angularly spaced pole pieces 5, each pole piece being laterally extended at the outer periphery of the rotor as indicated at 6. Located at each end of the rotor is an insulating member 7 which has projecting therefrom radial fingers 8 conforming generally to the pole pieces 5 but terminating just short of the lateral extensions 6. Thus each end of each pole piece and each end of the angular portion 5 is provided with an insulating member.

In the past it has been customary to insert into the angular space between each pair of pole pieces an insulating strip which is held in place by the lateral extension 6 which is V-shaped and extends from end to end of the rotor. Such pieces are small and difficult to handle, and difficult to assemble and store.

As a substitute for such separate insulating pieces I provide a single integral insulating strip

2

9. That strip is scored or marked for bending along the central axis 10, 10, and alternate sides of the strip are notched as at 11, 12, the notches extending inwardly in each case only as far as the center line 10, 10. The distance between the notch 11 on one side and the next notch 12 on the other side of the strip is substantially equal to the axial length of the rotor pole pieces 5.

The flat continuous strip indicated in Figure 4 10 may be bent along the axial line 10 and then each double section bent back upon itself at the notches 11 and 12 to produce the structure shown in Figure 5, where the curved members 13 are in alignment with the notches 11 and 12.

15. In assembling, one of the bent-back portions 14 will be inserted into the angular space between a pair of pole pieces 5. The natural elasticity of the paper will cause it to spring out as indicated at 15 beneath the overhanging member 6. The next double back section 16 will then be bent around the curved portion 13 as indicated, enclosing one of the radial strips 8, and this bent-back portion will be pressed into the next angular opening 17. This process continues until a V-shaped section of the insulating strip has been placed in each angular space between the pole pieces 5.

Under these circumstances there will be one 20 of the curved portions 13 at one end of each pole piece. The other end of each pole piece will be insulated by one of the radial members associated with the insulating member 8. Thus the entire body of the radial pole piece will be insulated, and the natural spring of the paper will 25 hold the insulation in place with the outer longitudinal edges masked by the overhanging members 6 on the pole pieces 5. Then, when electric wire is wound about each pole piece, it will be effectively insulated from the rotor by the strip and the star-shaped end insulating discs, and the overhang of the member 6 co-operating with the outward springing of the insulating sheet will insure that the windings will be placed within the insulating member and not between it and the 30 rotor.

As indicated, the notches 11 and 12 have substantial width. Their width measured in a direction parallel with the axis 10, 10 is of little consequence. They may be wide or narrow, 35 depending upon the width in a tangential direction of the rotor pole pieces. Under some circumstances these notches may even take the form only of a slit in the paper.

I claim:

55. 1. Insulating means for electric rotors and the

like, comprising a thin, flat longitudinally extended strip of flexible insulating material, longitudinally scored along its central axis, the strip being notched on opposed sides thereof at a plurality of spaced points along both sides, the notches alternating and extending inwardly substantially to the scored center line the opposite walls of the notches being parallel and perpendicular to the scored center line.

2. An insulating means for electric rotors comprising a plurality of flexible insulating strips, each strip being bent to V-shape along the longitudinal axis thereof, each strip being joined to an adjacent strip by a curved integral section substantially the width of one-half the strip.

3. In combination a rotor having a plurality of radial pole pieces angularly spaced one from another, an integral continuous insulating strip extending through the angular spaces between each pair of pole pieces, the part of the strip associated with each pair of pole pieces being integrally joined with the part of the strip associated with an adjacent pair of pole pieces a part of the strip masking one end of each of the pole pieces, the entire body of the strip being inside the outer periphery of the pole pieces.

4. An insulator for electric rotors comprising a plurality of flexible, thin insulating strips, each strip being bent to V-shape along its longitudinal axis and each strip being joined to an adjacent similarly bent strip by a section substantially half the width of the strip, said joining sections being alternately disposed on opposite sides of the strip.

5. In combination a rotor, including a plurality of radially disposed, angularly spaced pole pieces, lateral extensions projecting tangentially from the outer end of each pole piece, a continuous insulating strip located within the space defined by each pair of adjacent pole pieces, engaging the opposed walls of said pole pieces and masked by the laterally extended pole piece portions, the strip in each angular space being joined to the strip in the adjacent angular space by an integral portion whose width is substantially the same as the width of that portion of the strip engaging one wall of one pole piece.

6. In combination with a rotor having angularly spaced pole pieces, a single insulating strip whose width is approximately twice the radial extent of each pole piece, there being alternate notches on opposite sides of the strip, normal to the axial line of the strip, equalling in depth substantially half the width of the strip, the distance between a notch on one side of the strip and the adjacent notch on the other side being substantially equal to the axial length of the pole piece.

7. An insulator for electric rotors and the like, comprising a plurality of elongated insulating strips, each strip being folded about the longitudinal central axis thereof into a V-shape, each strip being attached to an adjacent strip by an integral piece whose width is one-half the width of the strip.

8. In combination with an electric rotor having a plurality of radially disposed elongated pole pieces, an insulator comprising a plurality of insulating strips, each substantially equal in length to the axial length of the pole pieces, each strip being folded about its longitudinal central axis into a V-shape adapted to lie in the angle between two adjacent pole pieces, each strip being connected to an adjacent strip lying in an adjacent angle between adjacent pole pieces by an

integral portion whose width is one-half the width of the strip.

9. An insulator for electric rotors and the like, comprising a plurality of elongated insulating strips, each strip being folded about the longitudinal central axis thereof into a V-shape, each strip being attached to an adjacent strip by an integral piece whose width is one-half the width of the strip, each integral joining piece being associated only with the adjacent branches of two adjacent V-shapes.

10. In combination with an electric rotor having a plurality of radially disposed elongated pole pieces, an insulator comprising a plurality of insulating strips, each substantially equal in length to the axial length of the pole pieces, each strip being folded about its longitudinal central axis into a V-shape adapted to lie in the angle between two adjacent pole pieces, each strip being connected to an adjacent strip lying in an adjacent angle between adjacent pole pieces by an integral portion whose width is one-half the width of the strip, each integral joining piece being associated only with the adjacent branches of two adjacent V-shapes.

11. An insulator for electric rotors and the like, comprising a plurality of elongated insulating strips, each strip being folded about the longitudinal central axis thereof into a V-shape, each strip being attached to an adjacent strip by an integral piece whose width is one-half the width of the strip, one of the joining strips joining one branch of the V at one end with a similar branch in an adjacent V-shaped section, the other strip joining the opposed branch of the first-mentioned V with the V-shaped strip at the other end of the first-mentioned V.

12. In combination with an electric rotor having a plurality of radially disposed elongated pole pieces, an insulator comprising a plurality of insulating strips, each substantially equal in length to the axial length of the pole pieces, each strip being folded about its longitudinal central axis into a V-shape adapted to lie in the angle between two adjacent pole pieces, each strip being connected to an adjacent strip lying in an adjacent angle between adjacent pole pieces by an integral portion whose width is one-half the width of the strip, one of the joining strips joining one branch of the V at one end with a similar branch in an adjacent V-shaped section, the other strip joining the opposed branch of the first-mentioned V with the V-shaped strip at the other end of the first-mentioned V.

13. Insulating means for electric rotors and the like, comprising a thin, flat longitudinally extended strip of flexible insulating material, longitudinally scored along its central axis, the strip being notched on opposed sides thereof, at a plurality of spaced points along both sides, the notches alternating and extending inwardly substantially to the scored center line, the opposite walls of the notches being parallel and perpendicular to the scored center line, each notch being bounded at its bottom by curved line generally tangent to the scored center line, the width of each notch being greater than the thickness of the strip of material.

14. In combination a rotor having a plurality of radial pole pieces angularly spaced one from another, an integral continuous insulating strip extending through the angular spaces between each pair of pole pieces, the part of the strip associated with each pair of pole pieces being integrally joined with the part of the strip associated with an adjacent pair of pole pieces, a

portion of the insulating strip masking one end of one pole piece and the opposite end of each adjacent pole piece.
